(57) **CLAIM**

The ornamental design for an apparatus for developing muscles, as shown and described.

DESCRIPTION

1. Apparatus for developing muscles
2. Apparatus for developing muscles
Reproduction 1.1 is a perspective view of a first embodiment of the apparatus for developing muscles;
Reproduction 1.2 is a perspective view of the apparatus for developing muscles in an alternate state;
Reproduction 1.3 is a top view of the apparatus for developing muscles;
Reproduction 1.4 is a perspective view of the apparatus for developing muscles in an alternate state;
Reproduction 1.5 is a perspective view of the apparatus for developing muscles in an alternate state;
Reproduction 1.6 is an enlarged partial perspective view of the apparatus for developing muscles;
Reproduction 1.7 is a perspective view of a handle element show in isolation and
Reproduction 2 is a perspective view of a second embodiment of the apparatus for developing muscles.
Cast shadows form no part of the claimed design.

1 Claim, 8 Drawing Sheets
